UNITED STATES PATENT OFFICE.

JOSEPH O. MAUBORGNE, LOUIS COHEN, AND GUY HILL, OF WASHINGTON, DISTRICT OF COLUMBIA.

ELECTRICAL SIGNALING.

Application filed April 8, 1921. Serial No. 459,530.

To all whom it may concern:

Be it known that we, JOSEPH O. MAUBORGNE, LOUIS COHEN, and GUY HILL, residing in Washington, District of Columbia, 5 have invented certain new and useful Improvements in Electrical Signaling, of which the following is a specification.

This invention relates to the art of radio signaling, and particularly receiving radio 10 signals and system for use in practicing same.

The object of the present invention is to secure a more selective tuning system, eliminating electro-static disturbances and other 15 interferences in the reception of radio signals.

In pending applications by J. O. Mauborgne and Guy Hill, Serial Numbers 389,720 and 389,450, and in pending applications by Louis Cohen and J. O. Mauborgne, 20 Serial Numbers 389,451 and 401,762, methods for receiving radio signals were described in which resonance wave coils are employed, and utilizing the wave development effects 25 produced by electrical excitations acting either on the resonance wave coils directly, or on an antenna to which the wave coils are electrically connected.

The present invention presents further 30 modification maturing from the aforesaid pending applications, but embodying additional novel features with the view of securing still greater improvements in the results desired, namely, more selective tuning, securing greater freedom from electro-static 35 disturbances and other interferences in the reception of radio signals.

Preferably, the general principles covering the uses of resonance wave coils for the 40 reception and transmission of radio signals have been fully described in the pending applications referred to above. The method involved in the present invention consists in the use of more than one wave coil, transferring 45 the energy of the received signal from one wave coil which constitutes part of an antenna system to another wave coil which has no physical connection to any part of the 50 antenna system, or to the wave coil associated with the antenna system. The energy transfer is accomplished through electro-static or magnetic or a combination of both 55 types of coupling between the wave coils; the indicating instruments being connected to the coupled wave coil. By this arrange-

ment a progressive elimination in interference and atmospheric disturbances is effected. Any interference effect which is not completely damped out in its passage through the first wave coil is further reduced in its travel through the second coupled wave coil. The signal effects on the other hand, do not suffer any material attenuation if the wave coils are properly adjusted in relation to the wave length of the signal so as to procure wave development effects on both wave coils, and the grid of a vacuum tube indicator is connected to a loop of potential on the second coupled wave coil. The difference in the propagational characteristics of sustained oscillations and impulses or damped oscillations on a conductor of distributed inductance and capacity has been fully discussed in the hereintofore identified pending applications of Louis Cohen and J. O. Mauborgne.

A progressive improvement may be obtained by using several wave coils successively coupled, the signal energy being transferred several times from one wave coil to another before it acts on the indicating instrument.

The principle of operation and the method of using our invention can better be understood by reference to the accompanying diagrammatic figures which show typical embodiments of the invention and form part of this specification.

In the accompanying drawings, Figure 1 is a diagrammatic view of the system for carrying out the invention in which one wave coil is connected to the antenna and another wave coil associated with an indicating instrument, is coupled to the wave coil of the antenna system.

Figure 2 differs from Figure 1 in that a closed loop aerial is used in place of an open aerial.

In the embodiment shown in Figure 3 no ground connection is used for the antenna system.

Figure 4 shows an arrangement of the invention in which the aerial is grounded through a tuned loop circuit and the wave coil is connected directly to a point on the antenna system.

The modification shown in Figure 5 consists in the use of an electro-static coupling between the antenna and the wave coil.

Figure 6 differs from Figure 5 only in that

the tuning inductance is in series with the plate condenser instead of in parallel.

Another modification is shown in Figure 7 in which a wave coil is placed in the proximity of a tuned antenna system and utilizing the coupling between the antenna system and the wave coil.

Figure 8 shows still another modification in which three wave coils are employed, the antenna being connected to one wave coil and the signal energy being transferred through an intermediary wave coil before it reaches the third wave coil to which the indicating instrument is connected.

15 The modification of the invention shown in Figure 9 consists in coupling two systems of wave coils to the wave coil associated with the antenna for the purpose of receiving simultaneously two signals of different frequencies.

Having particular reference to the drawings and in connection with which like characters of reference will designate corresponding parts thereof, in Figure 1, the antenna 1 is connected to a variable condenser 2 and in series with the wave coil 3. 4 indicates an adjustable metal tube surrounding part of the wave coil 3 and being grounded at the point 7 through a tuned loop circuit, 30 consisting of a variable condenser 6 and variable inductance 5 joined in parallel. Another wave coil 8 is electro-statically associated with the indicating instrument 10 through a metal ring 9, sliding along the wave coil 8. If a vacuum tube indicator is used, the sliding ring 9 is connected to the grid which is here represented by 11.

The principle of operation is as follows:

In Figure 1 the tuning of the antenna system is accomplished by varying the capacity 2, the inductance 5 and capacity 6 of the loop circuit, and varying the position of the metal tube 4 on the wave coil 3. By properly adjusting all the above elements in relation to each other and in relation to the wave-length of the signal, extremely sharp tuning is obtained. By adjusting the length of the wave coil 3 in relation to the wave-length of the signal, stationary waves on the coil 3 are established, the energy of which is transferred to the wave coil 8 through the medium of the coupling between them, due to proximity of the wave coils 3 and 4. By varying the relative positions of the two wave coils, 3 and 8, the degree and character of the coupling is varied. The coupling may be either electro-static or electro-magnetic or generally a combination of the two types of coupling. The energy transferred from wave coil 3 effects a wave development on wave coil 8, setting up stationary waves thereon. By connecting the grid 11 of the vacuum tube indicator 10 to a loop of potential point on coil 8, a large signal effect is obtained. The connection between the

indicator 10 and the wave coil 8 may be either direct or electro-static, as shown in the diagram.

In the case of any foreign disturbances which may be in the nature of an impulse or damped oscillations acting on the antenna, the effects are rapidly attenuated as the disturbance travels along the wave coil 3 and any residual effect which may reach the end of the coil 3 and be transferred through coupling to the wave coil 8, is still further attenuated as it progresses along the wave coil 8 and therefore, very little, if any, effect on the indicating instrument is obtained.

Figure 2 differs only from Figure 1 in 80 that a closed loop aerial is used, consisting of loop 12 and variable condenser 13. This loop aerial system is connected to the wave coil 3 through a variable condenser 14. In this arrangement, the loop circuit of inductance 5 and capacity 6, which is grounded at the point 7, may or may not be used, although under certain conditions, the addition of this tuned loop circuit is useful. The 85 operation of this arrangement is practically 90 the same as that described in connection with Figure 1.

The embodiment of the invention shown in Figure 3 consists in the use of an ungrounded antenna. In this case the antenna 1 serves only for the purpose of picking up the signal energy and transferring it to the wave coil 3, through adjustable connection 26, setting up a wave development on that coil and again transferring such energy from wave coil 3 to wave coil 8 and through the coupling which exists between them because of the relative positions of the two wave coils with respect to each other.

The modification shown in Figure 4 consists in the use of a tuned antenna circuit, comprising the aerial 1, variable condenser 2 and loop circuit 5-6, and ground 7. The wave coil 3 is connected directly to the antenna through the adjustable contact point 26. The incoming signal sets up oscillations in the antenna system and impresses such oscillations on the wave coil 3, effecting wave developments on that coil and again transferring the energy to the wave coil 8 105 which is associated with suitable indicator 10, connected electro-statically through the ring 9. The filament electrode terminal 27, of the vacuum tube 10 is grounded at the point 7. In some cases it is preferable to omit the ground connection 7'.

The modification shown in Figure 5 consists in the use of a tuned antenna system comprising antenna 1, a variable inductance 15, loop circuit 5, 6, and ground 7. At two points 28 and 29 of the variable inductance 15, two metal plates 16 and 17 are connected, said plates being placed in close proximity to the wave coil 3. In this arrangement the wave coil 3 is placed in an electro-static field 125 130

of the condenser formed by the two plates 16 and 17, thereby inducing the transfer electro-statically of signal energy to the wave coil 3 and effecting a wave development on that coil. The indicating instrument 10 is connected electro-statically through the ring 9 to the wave coil 3.

The modifications shown in Figure 6 consist in the use of a tuned antenna system 10 coupled electro-statically with a wave coil. The tuned antenna system consists of antenna 1, condenser formed by metal plates 16 and 17, variable inductance coil 18, a loop circuit 5, 6 and ground 7. Plates 16 and 17 being placed in close proximity to wave coil 3, producing an electrical charge on the said wave coil 3, and setting up a wave development on it, the indicator 10 being connected electro-statically through the ring 9 to the wave coil 3. The distance of plates 16, 17 from wave coil 3 and from each other can be varied as desired. Also, the exact physical form of plates 16 and 17 are not indicated as they can assume any shape desired.

In Figure 7 the wave coil 3 has no physical connection with the antenna system. The signal energy picked up by the antenna is transferred to the wave coil 3 through the magnetic or static coupling existing between the wave coil 3 and the antenna system 1, 2, 18, 7, because of the proximity of the wave coil 3 to the antenna system. In this case also, a wave development is established on the wave coil 3 and the indicating instrument 10 is connected electro-statically through the ring 9 to the wave coil 3.

In the modification shown in Figure 8 three wave coils are employed. An untuned antenna 1 is connected electro-statically 40 through the ring 19 to the wave coil 3. A wave development is established on wave coil 3, the energy being transferred to wave coil 20, thus establishing a wave development on that coil and again transferring the energy to the wave coil 21 which is associated with an indicator 10 through the metal ring 9. The purpose of this arrangement is to secure a greater attenuation of any interfering signal by having it pass 45 through three wave coils before it reaches the indicating instruments, thereby securing a progressive reduction in the interference effects and hence securing still greater clearness of the signal received. The wave length of the wave coil 20 should be adjusted to the length of the signal desired to be received.

In Figure 9 an arrangement is shown 60 whereby a wave coil system is utilized for diplex work, that is, receiving simultaneously on the same antenna, two signals of different frequencies. The antenna 1 is connected electro-statically through the ring 19 to some point on the wave coil 20, 21. The 65 relative parts of the wave coil 20, 21, are

each adjusted for different wavelengths so that a signal of one wavelength will establish a wave development on the part of the wave coil which may be designated by 19, 20, and the signal of another frequency establishing a wave development on the part of the coil designated by 19, 21. The wave coils 24, 25 are adjusted for the frequency of the signal which is picked up by the antenna and part of the wave coil 19, 20 and similarly the wave coils 22, 23, are each adjusted to be in resonance for the frequency of the signals picked up by antenna 1 and part of wave coil 19, 21. The detectors 1, 10' associated, respectively, with the coils 22, 25, through the metal rings 9, 9' will each respond only to the signal acting upon the coil with which the detector is associated.

It is obvious that various other modifications of the circuit arrangements may be made without departing from the spirit or scope of the invention. For the purpose of illustration, only two wave coils are shown in nearly all of the figures utilizing only one energy transfer from one wave coil to another. Obviously, more than two wave coils can be used for successively transferring the energy from one wave coil to another and thereby effecting a greater attenuation of any residual disturbance which may exist in any one coil. Also in all the figures the indicator shown may be a simple vacuum tube detector or an amplifier or an oscillating detector including an oscillating circuit with the necessary regenerative coupling associated with it for the purpose of receiving undamped waves or utilizing the regenerative effects to obtain a greater efficiency. Also in all the figures except Figure 4, the detector, or tuned receiving set associated with detector is shown as being free from any ground connection. In some cases it may be preferably to use a ground connection to the indicator as shown in Figure 4, for the arrangements shown in all the other figures. It is clearly within the province of the invention to introduce these variations.

We claim:

1. In a system for radio signaling, an antenna, a wave coil adapted for the production of wave development effect thereon by signal energy, and operatively associated with said antenna, means for transferring said signal wave energy through an electro-static coupling to another wave coil which is operatively associated with a detecting instrument.

2. In a system for radio signaling, an ungrounded antenna, wave coils adapted for the production of wave development effect thereon, one of said wave coils being operatively associated with an adjustable grounded metal tube, the other of said wave coils being operatively associated with an

indicating instrument, means for transferring the received signals acting on the ungrounded antenna through said two wave coils which are in electro-static and electro-
5 magnetic relation to each other.

3. In a system for radio signaling, an antenna, a plurality of wave coils, each of said valve coils being adapted for the production of wave development effect thereon, 10 one of said wave coils being connected to the said antenna, means for transferring successively, electro-statically, and electro-magnetically the wave energy to the several wave coils, the last of said wave coils being operationally associated with an indicating instrument.

4. In a system for radio signaling, an antenna, a wave coil adapted for the production of wave development thereon by signal energy, and operationally associated with said antenna, the point of connection of the antenna to said wave coil being so adjusted that the antenna and either part of the wave coil may be adjusted to be in resonance for
20

two different frequencies, thereby making 25 the system responsive to two signals of different frequencies, the two parts of said wave coil being respectively coupled to other wave coils suitably adjusted for the selective reception of one of said two frequencies and operationally associated with indicating instruments.

5. A system for radio signaling comprising an antenna electro-statically connected to a wave coil, the point of connection of the said antenna to the said wave coil dividing the said wave coil into two parts in such a way as to make each part respond to a definite frequency, the two frequencies being different from each other, two systems 35 of wave coils being associated electrically with each part of the first said wave coil and separate indicating instruments associated with each of said systems of wave coils.
